No. 629,272.

Patented July 18, 1899.

W. RICHARDS

HARROW.

(Application filed Sept. 10, 1898.)

(No Model.)

UNITED STATES PATENT OFFICE.

WILLIAM RICHARDS, OF BELLBROOK, OHIO.

HARROW.

SPECIFICATION forming part of Letters Patent No. 629,272, dated July 18, 1899.

Application filed September 10, 1898. Serial No. 890,625. (No model.)

To all whom it may concern:

Be it known that I, WILLIAM RICHARDS, a citizen of the United States, residing at Bellbrook, in the county of Greene and State of Ohio, have invented certain new and useful Improvements in Harrows, of which the following is a specification, reference being had therein to the accompanying drawings.

This invention relates to certain new and useful improvements in harrows.

The objects of my invention are to provide suitable means for connecting an ordinary harrow proper with a sulky or carriage in such a manner that the draft strains which are applied directly to said harrow proper will cause the power required to move said carriage along to act to hold the harrow in the soil, no matter what the condition of the soil or the depth the harrow may be stirring the ground; to provide suitable means for setting said harrow proper so that it will run shallower or deeper in the soil, as desired, and to provide means for permitting the harrows to accommodate themselves to the contour of the land being cultivated.

My invention also relates to details of construction and arrangement hereinafter appearing, and particularly pointed out in the claims.

In the accompanying drawings, on which like reference-letters indicate corresponding parts, Figure 1 is a vertical sectional view of my improved harrow, the section being taken on the line xx of Fig. 2 and looking in the direction of the arrow; Fig. 2, a plan view of my improved harrow complete, and Fig. 3 a detail view of the bifurcated push-rod and its connection with one of the couplings on the harrow proper.

The letter A represents an axle mounted in supporting-wheels B. To the axle is attached a pole C, to which is secured a cross-bar D by means of a bolt E or in any other suitable manner. In order to additionally secure this cross-bar in position, I provide side rails F, connecting-bars G, and connecting-rods H, which connect the axle and cross-bar together, the rods H also acting as lateral braces. These several parts constitute a rigid frame structure, to which harrows proper, I, are attached in a manner presently to appear.

Beneath the frame structure and between the ground and supporting wheels is arranged a harrow, say, of the spike-toothed pattern,

though it may have other kinds of teeth. 55 This harrow is formed of two sections to more readily accommodate itself to the surface of the ground which is to be harrowed. These sections are connected together by means of a connecting-bar J, secured at its ends to the respective sections by means of pull rods or links K, and also through their intersection with the carriage-frame structure above referred to. To this connecting-bar the draft strains are directly applied. In order to hold it from 65 dropping upon the ground, I provide chains L, which connect it with the cross-bar D of the carriage-frame.

To effect the depression of the harrow proper into the ground, I provide a pair of 70 push-rods a, one for each section, which are T-shaped at their upper ends, as shown at a', and are pivotally mounted in bearings M. This T-shaped formation gives to the push-rods great lateral rigidity. At their lower 75 ends these push-rods are bifurcated and are each pivotally secured to their respective couplings to give play in a vertical direction, but are perfectly rigid in a lateral direction, thereby preventing the harrow-sections from 80 crowding to or from each other. These couplings are composed of a shaft b, rotatably mounted in bearings b', and a stop-arm N, fitting between said bifurcations, which arms have lugs or projections O and P, respectively, 85 adapted to engage with said push-rods according to the position of the harrow-sections relative to a horizontal line—that is, when the harrow is passing over dead-furrows and uneven land the harrow-sections may rise or 90 fall a limited amount until one or the other of the lugs O or P engages with the push-rod. This up-and-down movement of the harrow-sections permits the harrow-teeth to remain in the ground a predetermined distance in- 95 stead of pulling out, and thus failing to stir the ground to the depth desired. The shafts of the couplings being rotatably mounted in the bearings b', the harrow-sections may freely rock in a lateral direction, so that all the harrow-teeth c may remain in the soil, no matter 100 whether on uneven ground or not, either in the line of travel or in a lateral direction.

I will now refer to the mechanism for limiting the depth the harrow-teeth are to work 105 in the soil and for lifting them out of the ground. It will be observed that to each of the side rails F, I have pivotally mounted a

hand-lever Q by means of a bolt R. These hand-levers each carry a hand-operated detent S, which may be engaged with and disengaged from the toothed segment T, mounted upon said side rails F. To the lower end of the lever Q is attached a chain V, which hooks over one end of a lever W, also pivoted to the siderail F by a bolt X or in any other suitable manner. A ring d on the other end of said lever serves as a connection for three suspension-chains e, connected to three different points on one of the harrow-sections proper. These devices suspend the harrow-sections in the desired positions or depth relatively to the ground and also act to lift one or both of said sections when the machine is to be transferred from place to place or in turning, if desired. The flexible character of these suspension devices prevents them from interfering with the wobbling and uneven movements of the lower sections as they travel over the ground.

Operation: In starting the harrow in the field the lever Q is operated to lower the harrow the required or desired depth to properly stir the soil. The draft strains pull forward on the harrow proper, which causes the push-rods to operate on the carriage to cause it to travel with the harrow proper, it being of course understood that the outer end of the pole is supported by the neck-yoke (not shown) carried by the draft-animals. It will thus be understood that the resistance of the sulky or carriage, determined by its weight, is utilized to press down upon the harrow proper. This would cause the teeth of the harrow proper to go deeper and deeper into the soil; but this tendency is governed by the suspension-chains and lever mechanism, so that the resistance of the sulky to travel over the ground serves to keep the teeth of the harrow proper to this predetermined depth in the soil, according to the wishes of the operator.

45 A seat X' is secured near the inner end of the pole for the accommodation of the operator, whose weight, in addition to the weight of the sulky, assists in this holding-down tendency.

50 Having thus fully described my invention, what I claim as new, and desire to secure by Letters Patent, is—

1. In a harrow, the combination with a sulky and a harrow proper, of one or more pivoted push-rods for connecting said harrow proper with said sulky, means to limit the vertical oscillation of said rod and draft appliances for applying the draft strain directly to said harrow proper, whereby said draft strains will be transmitted through said harrow proper to said sulky to cause the latter to travel with the former.

2. In a harrow, the combination with a sulky and a harrow proper, one or more pivoted push-rods for connecting said harrow proper with said sulky, means to limit the vertical oscillation of said rod and draft appliances

for applying the draft strains directly to said harrow proper, whereby said draft strains will be transmitted through said harrow proper to said sulky to cause the latter to travel with the former, of suspension mechanism for limiting the depth of the harrow-teeth within the ground, substantially as shown and described. 75

3. In a harrow, the combination with a sulky and a harrow proper, of one or more pivoted push-rods for connecting said harrow proper to said sulky, means to limit the vertical oscillation of said rod, draft appliances for applying the draft strains directly to said harrow proper, and suspension mechanism consisting of suitable chains and lever mechanism for limiting the depth of the harrow-teeth within the soil and for raising them out of the soil, substantially as shown and described. 80

4. In a harrow, the combination with a sulky and a harrow proper, of one or more push-rods pivoted at one end to said sulky and at their other end to a coupling carried by said harrow proper, means to limit the vertical oscillation of said rod, draft appliances for applying the draft strains to said harrow proper, and suspension mechanism consisting of a pair of pivoted levers connected with each other, and a set of suspension-chains connected to one of said levers and to said harrow proper, for limiting the depth of the harrow-teeth within the soil and for raising them out of the soil, substantially as shown and described. 90

5. In a harrow, a push device, and coupling composed of a rod and a shaft pivoted together, the shaft having an arm adapted to form a stop to limit the relative position of the rod and shaft. 105

6. In a harrow, a push and coupling device consisting of a rod and a shaft pivoted together, the rod being bifurcated and the shaft having a stop-arm extending between the bifurcations and having lugs or projections which form stops to limit the relative position of the rod and shaft. 110

7. In a harrow, a push and coupling device consisting of a rod and shaft pivoted together, said rod being pivoted to the frame of a sulky and said shaft pivoted on said harrow, and means for limiting the pivotal movement at the connection of the rod with said shaft; substantially as specified. 115

8. In a harrow, a push and coupling device consisting of a rod and shaft pivoted together, said rod being pivoted to the frame of a sulky and said shaft pivoted on said harrow, means for limiting the pivotal movement at the connection of the rod with said shaft, and a draft device for applying the strain directly to said harrow; substantially as specified. 120

In testimony whereof I affix my signature in presence of two witnesses.

WILLIAM RICHARDS.
